Kenneth D. Berdan, Detroit, Mich., assignor to Michigan Electrotype and Stereotype Company, Detroit, Mich., a corporation of Michigan

Application March 19, 1934, Serial No. 716,406

5 Claims. (Cl. 206—62)

This invention relates generally to shipping cases and refers more particularly to improvements in cases of the type having provision for protecting articles from injury.

5 One of the principal objects of this invention is to provide a relatively simple and inexpensive packing case so constructed as to prevent shocks imparted to the case from being transmitted to the article enclosed thereby. In accordance 10 with this invention the foregoing results are realized by providing cushioning means above as well as below the enclosed article and by holding the article in the case with the edges of the former spaced a substantial distance from the side edges of the latter. To this end the invention contemplates forming the case of a material inherently possessing the cushioning qualities previously set forth and in addition contemplates the provision of unique means for positively holding the article in spaced relation to the side edges of the case.

Another object of this invention resides in mounting the article upon a filler formed separately from the case and insertable into the latter with the article in assembled relation therewith. If desired the filler may also be formed of a material inherently possessing cushioning qualities in which event a double thickness of material having this characteristic would be provided at one side of the article.

A further object of this invention resides in the provision of means on the filler for holding the article with the edges thereof in substantial spaced relation to the side edges of the case.

35 In the specific embodiment of this invention the aforesaid means is in the form of tabs or tongues severed from the filler and foldable over the side of the article opposite the side resting upon the filler. Thus the tabs or tongues perform the 40 additional function of spaces between the adjacent side of the article and opposite side of the case.

In addition to the foregoing this invention contemplates a novel construction of case capable 45 of being inexpensively manufactured and readily opened or closed. The particular construction of the case as well as the foregoing objects will be made more apparent as this description proceeds, especially when considered in connection with the accompanying drawing, wherein:

Figure 1 is a perspective view of a shipping case constructed in accordance with this invention;

Figure 2 is a transverse sectional view through 55 the case;

Figure 3 is a sectional view taken on a plane at right angles to the plane of the section of Figure 2;

Although it will be apparent as this description proceeds that a packing case constructed in accordance with this invention may be employed for shipping various types of articles of different sizes, nevertheless, it finds particular utility when used in shipping substantially flat plate-like fragile articles, and accordingly, the packing case selected to illustrate a practical embodiment of this invention is shown herein as particularly designed for the above purpose.

In the interests of simplicity and economical manufacture the packing case comprises a container 10 formed of a single piece of double faced corrugated paper-board having a substantially flat base 11 of a dimension predetermined in dependence upon the particular size of the article 12 it is desired to enclose. In the present 20 instance, the base 11 forms the bottom or one side of the case and the area of this side is substantially greater than the area of the plate-like article 12 it is desired to enclose so as to permit supporting the article with the edges thereof in 25 lateral spaced relation to the side edges of the base 11.

The opposite or top side 13 of the case is formed by the flaps 14 which are connected to the edges of the base 11 through the medium of end sections 15 forming the side walls of the case when the flaps are folded over the base in the manner shown in either Figure 2, or Figure 3. The flaps 14 are of course of such dimension as to cooperate in the folded position thereof to completely cover the article 12 and the width of the sections 15 is predetermined to impart the desired thickness to the case.

Due to the corrugated sheet 16 interposed between the inner and outer wall surfaces of the 40 blank forming the container 10, the article 12 within the case is, in effect, yieldably supported in spaced relation to the outer surface of the case. However, the cushioning action effected by the corrugated sheet 16 may be increased and 45 the protective qualities of the case correspondingly enhanced by supporting the article 12 upon a filler 17 formed of the same material as the container, or in other words, of double faced corrugated paper-board. The filler 17 preferably 50 corresponds in dimension to the base 11 of the case and loosely rests upon the inner surface of the base so as to cooperate with the latter in forming a double thickness of corrugated paper-board beneath the article 12.

In the present instance the article 12 is centrally positioned upon the inner face of the filler and held in assembled relation thereto by means of tabs or tongues 18 severed from the filler and 5 capable of being folded over the article in the manner clearly shown in the drawing. In the specific embodiment of the invention four tabs or tongues are severed from the filler and the end tabs 19 are folded over opposite sides of the 10 plate-like article 12, while the side tabs 20 are folded over the sides of the article 12 adjacent the aforesaid sides. Thus it will be seen that lateral shifting of the article 12 to such an extent as to permit one edge of the same to engage one 15 of the side walls of the case is prevented and, accordingly severe shocks may be imparted to the end walls 15 without any danger of damaging the article 12.

The filler with the article 12 in assembled 20 relation thereto is of course placed upon the inner face of the base 11 prior to folding the flaps 14 and it necessarily follows that when the flaps 14 are folded to the position thereof shown in either Figure 2 or Figure 3, the inner surfaces 25 of the flaps rest upon the tabs or tongues 18. Consequently, at least a double thickness of the corrugated paper-board may also be considered to be disposed above the article 12 as well as below the same. In view of the double cushioning action afforded above and below the article 12 considerable shocks may be subjected to the top and bottom walls of the case without damaging the enclosed article and in view of the fact that the 30 tabs 18 hold the article in a position with the edges thereof spaced substantially from the side walls 15 of the case abnormal shocks may be imparted to these side walls without damaging the article. It may be pointed out at this time that although the tabs prevent excessive lateral 35 displacement of the article relative to the case, nevertheless, the formation of the flaps is such as to accommodate articles of different sizes.

From the foregoing it will be observed that I 40 have provided a shipping case of such construction as to protect the article therein against injury either by dropping the case or otherwise roughly handling the same. It will also be observed that by reason of the foldable flap and tab combination the package may be readily 45 manipulated to insert the article into the same and to remove the article therefrom. It will further be apparent that by reason of the material employed in forming the case and due to the particular construction of the same, the cost 50 of manufacture is extremely low.

Although only one specific embodiment has been selected to illustrate the principles of this invention, nevertheless, it is to be understood 55 that these principles may be obtained by various different specific constructions, and reservation is made to make such changes in the construction of the case as may come within the purview of the accompanying claims.

60 65 What I claim as my invention is:

1. A shipping case for articles comprising bottom, top and side walls defining an area within the case substantially greater than the area of the article to be shipped, and means for holding the article within the case with the edges of the article spaced a substantial distance inwardly from the side walls of the case, said means including tabs spaced inwardly from said side walls and fixed in the case, said tabs being foldable 70 over one side of the article to hold the opposite

side of the latter in engagement with the adjacent wall of the case and also being so located with respect to the article as to prevent shifting movement of the article in the case.

2. A shipping case for articles comprising bottom, top and side walls defining an area within the case substantially greater than the area of the article to be shipped, and means for holding the article with the side edges thereof spaced a substantial distance inwardly from the side walls 10 of the case, including tabs spaced inwardly from the side walls of the case and fixed in said case, said tabs being foldable over the article into engagement therewith and held in their folded positions by one wall of the case and also being 15 so located with respect to the article as to prevent shifting movement of the same in the case.

3. A shipping case for articles comprising a wall having an area substantially exceeding the area of an article to be enclosed in the case, 20 flaps at the marginal edges of the wall aforesaid foldable to form side walls and to form a wall opposite the first-named wall, a filler seated upon the first-named wall with the marginal edge portions thereof engaging the side 25 walls of the case to prevent shifting movement of the filler relative to the case, and tab means for holding an article to be shipped on the filler with the side edges of the article spaced a substantial distance inwardly from the marginal 30 edges of the filler, including members spaced inwardly from the edges of the filler and fixed to the latter, said members being so located with respect to the article as to engage the portions 35 of the side edges of the article required to prevent shifting movement of the article in the case.

4. A shipping case for articles comprising bottom, top and side walls defining an area within the case substantially greater than the area of the article to be shipped, a removable filler 40 seated upon the bottom wall of the case with the marginal edges thereof engaging the side walls of the case to prevent shifting movement of the filler within the case, and tab means for holding an article to be shipped upon the top 45 surface of the filler with the side edges of the article spaced a substantial distance inwardly from the side walls of the case, including members carried by the filler and spaced inwardly from the side edges of the filler, said members 50 being so located with respect to the article on the filler as to engage the side edge portions of the article required to prevent shifting movement of the article in the case.

5. A shipping case for articles comprising bottom, top and side walls defining an area within the case substantially greater than the area of the article to be shipped, a filler seated upon the bottom wall of the case with the marginal 60 edges thereof engageable with the side walls 65 of the case to prevent shifting movement of the filler within the case, and means for holding an article on the top surface of the filler with the side edges of the article spaced a substantial distance inwardly from the side walls of the case, including tabs spaced inwardly from the side edges of the filler and secured to the filler, said tabs being foldable over the top surface of the article and held in their folded positions by the 70 top wall of the case and also being so located with respect to the article as to prevent shifting movement of the article in the case.
